UNITED STATES PATENT OFFICE.

JOSEPH V. ROBINSON, OF NEW HAVEN, CONNECTICUT.

AUTOMATIC TRAIN-PIPE COUPLING.

1,212,684.

Specification of Letters Patent. Patented Jan. 16, 1917.

Application filed December 21, 1912, Serial No. 738,014. Renewed April 11, 1916. Serial No. 90,522.

To all whom it may concern:

Be it known that I, JOSEPH V. ROBINSON, a citizen of the United States, residing at New Haven, in the State of Connecticut, have invented certain new and useful Improvements in Automatic Train-Pipe Couplings, of which the following is a specification.

The object of the present invention is to increase the efficiency and utility of automatic train pipe couplings in the direction of promoting the interchangeability of different types of couplers.

One of the known types of couplers is provided with pin-and-funnel guides for bringing the openings of the train pipes into register to connect the pipes of one car accurately with those of another. Another type of coupler is provided with flaring wing-like guides for the same purpose, which may be briefly designated as wing-guides. According to my present invention I construct both wing-guide couplers and pin-and-funnel couplers so that either will automatically couple to one of the same kind or one of the other kind. Cars in the same train equipped in part with the wing-guide couplers and in part with the pin-and-funnel couplers will all couple together in so far as the train pipes are concerned, regardless of the distribution of the several types of couplers.

The invention will be more fully explained in connection with the accompanying drawings, in which:

Figure 1 is a side elevation showing a coupler of the pin-and-funnel type in coupled relation to a coupler of the wing-guide type. Fig. 2 is a side elevation of the pin-and-funnel coupler shown in Fig. 1, partly in section on the line 2--2 of Fig. 3. Fig. 3 is a front or end view of the pin-and-funnel coupler shown in Fig. 2. Fig. 4 is an end view of the two couplers shown in Fig. 1. Fig. 5 shows the manner of assembling the pin-and-funnel coupler shown in the foregoing figures. Fig. 6 illustrates the application of the principle of the present invention to a coupler having three pipe connections. Fig. 7 is a partial section on the line 7--7 of Fig. 6. Fig. 8 shows in detail the disks or abutments used as bearing points for the head.

Referring to Figs. 1 to 5 of the drawing 65 10, 11 indicate the draw bars of two car

couplers which are shown coupled together; 12, 13 indicate ribs extending down from the couplers and 14, 15 indicate brackets connected to the ribs 12, 13 and adapted to support the base members A, A' which 60 support the automatic train pipe couplings.

As shown in the drawings, the base member A supports a wing-guide coupling member, while the base A' supports a pin-and-funnel coupling member, these coupling 65 members being adapted to interlock and cooperate, as will be presently explained.

Referring particularly to Figs. 2 to 5 inclusive, 16 indicates a coiled spring, preferably tapering and constructed of a tapering rod as shown in the drawing. One end of this spring is securely seated in the base A', while the other end surrounds and is connected to a sleeve 17 which is adapted to slide upon the pipe 18 forming the terminal member of the train pipe. The sleeve 17 supports the forward end of the pipe 18 and integral with the sleeve is the coupling head B' which carries the guide pin 19 and the guide funnel 20. The forward end of 80 the spring 16 enters the head B', as shown at 21, Fig. 4, and the pin-and-funnel members are held yieldingly in their normal position by the spring. These members are free to rock about the axis of the pipe 18 85 to a limited extent in one direction and also free to move rearward on said pipe as indicated in Fig. 5. They may thus yield and are adapted to move out of the way, so far as may be necessary, to permit a 90 coupler of the wing type to adapt itself accurately to the pin-and-funnel coupler by the means which will be presently described.

On the forward end of the pipe 18 are fixed two oppositely disposed auxiliary 95 guide members or supports 22, 23 of somewhat irregular conformation and adapted to conform to the inner surfaces of the wing guides 29, 30 of the opposing coupling, to be presently described, to cause the opening of the pipe 18 to register accurately with the corresponding opening in the wing-guide coupler. The shape of the guides 22, 23 will depend upon the particular shape of the wing-guide coupler with 100 which they are intended to coöperate, but I show them of convex formation as will appear from the drawing. The guides 22, 23 have stop projections 24, 25 lying in substantially horizontal and vertical planes 110

against which the arms carrying the pin-and-funnel members normally abut, as shown in Fig. 3. The guide members 22, 23 are symmetrical with respect to the axis 5 of the pipe 18, the opening of said pipe being centrally arranged between them and provided with a suitable flexible gasket 26. The pipe 18 passes loosely through the base A' and is free to have a universal movement therein to a limited extent. It is prevented from turning in the base by means of a key 27, shown in Fig. 5, and the head B' is slotted at 28 to permit it to pass over the key 27.

15 In Figs. 1 and 4 I have shown a coupler head of the well known wing-guide type but supported in substantially the same manner as the pin-and-funnel coupler above described. B indicates the head of this coupling, the same being supported by the spring 16 with freedom to recede and to turn in either direction. The spring, however, holds the coupler head normally in the proper position for coupling. On the head 20 B are the outwardly diverging wing-guides 25, 30.

30 In Figs. 2 and 3 there are shown disks or abutments 31 projecting slightly from the face of the auxiliary guides 22, 23. These 35 are preferably arranged upon a diametrical line through the center of the pipe 18 and are intended to hold the meeting faces of the couplers slightly apart to prevent foreign substances from interfering with accurate and close contact of the gaskets 26. These abutments may be in the form of headed pins of tough and suitably hardened metal set into the guides, one form of such abutments being shown in detail in Fig. 8.

40 It will be understood that the pin-and-funnel type of coupler described will also 45 accurately connect with another coupler of that type. The operation of either of these couplers in connection with another coupler 50 of the same type is well known. When a car provided with one of the pin-and-funnel couplers is coupled to a car provided with one of the wing-guide couplers the auxiliary guides 22, 23 of the pin-and-funnel coupler 55 come into play and coöperate with the wing-guides of the opposing coupler to accurately bring the pipe members of the two couplers into correct register. If the pin-and-funnel guides are in the way of the wing-guides the former guides yield either by moving backward, or turning, or both, as heretofore described, and hence do not prevent the auxiliary guides from accurately coöperating with the wing-guides. Neither do the auxiliary 60 guides prevent the pin-and-funnel coupler from accurately coöperating with another pin-and-funnel coupler whether it be provided with the auxiliary guides or not.

In Figs. 1 to 5 I have shown the invention 65 incorporated in couplings suitable for

freight cars, that is, couplings having but one fluid duct for conveying the air-brake air.

In Figs. 6 and 7 I have shown the invention as applied to a three-duct coupler 70 adapted for passenger cars, the ducts being respectively for the heating system, the air-brake and the signal air. Referring to these latter figures B² indicates a coupler head carrying a pin 35 and funnel 36 and having 75 openings 37, 38, 39 for air and steam connections. Adjacent the arms 40 and 41 which carry the pin and funnel respectively are auxiliary guides or supports 42, 43 which are adapted to coöperate with the wing-guides of a coupler of the wing type. In Fig. 6 there are shown in dotted lines wings 44, 45 having guiding surfaces 46, 47 which coöperate with the auxiliary guides 42, 43 to bring the openings in the wing-guide 25 coupler accurately into register with the openings in the pin-and-funnel coupler.

It will be noted that in the various forms of the invention the auxiliary guides have considerable depth and that the guiding surfaces are parallel with the axes of the couplers as shown particularly in Figs. 2, 5 and 7. The inner portions of the guiding surfaces of the wing-guides are preferably constructed in the same way so that in and 95 near the final adjustment of one type of coupler to the other in coupling the contacting surfaces are parallel, which promotes accuracy in register between the couplers and prevents movement out of register while the 100 opposing couplers are in mutual operative position.

Having thus described the invention what is claimed as new is:

1. In an automatic train pipe coupling, 105 the combination with a perforated coupling head, of means on said head for interchangeably receiving a perforated coupling head of different construction and for maintaining said last mentioned head in place 110 with said perforations substantially aligned.

2. In an automatic train pipe coupling, the combination with a perforated coupling head, of spaced shoulders connected with 115 said head for interchangeably receiving a perforated coupling head of different construction and for maintaining said last mentioned head in place with its perforation aligned with the perforation of the first mentioned head.

3. In an automatic train pipe coupling, 120 the combination with a coupling head, of means for interchangeably receiving a coupling head of a different type, said means comprising a support connected with the 125 first mentioned head and having a seat with which the guides of the last mentioned head register in coupling.

4. In an automatic train pipe coupling, the combination with a coupler of one construc- 130

tion, of means for adapting said coupler to couple with a coupler of a different construction comprising auxiliary guides on the former coupler for receiving the usual guides upon the latter coupler.

5 5. In an automatic train pipe coupling, the combination with a coupler having the usual guiding members, of auxiliary guides adapted to coöperate with the guide members of a coupler of another type.

10 6. In an automatic train pipe coupling, the combination with a coupler having guides of one construction, of a coupler having guides of a different construction, 15 and means connected with the first mentioned guides coöperating with the last mentioned guides whereby said couplers are made interchangeable.

7. In an automatic train pipe coupling, 20 the combination with a coupler having pin-and-funnel guides, of auxiliary guides to adapt said coupler to coöperate with a coupler having a different type of guides.

25 8. In an automatic train pipe coupling, the combination with a coupler having pin-and-funnel guides, of relatively movable auxiliary guides adapted to coöperate with the wing-guides of a coupler of the latter type.

30 9. In an automatic train pipe coupling, the combination with a coupler having guiding members and auxiliary guides, of means supporting the first-named guides for movement to permit another coupler to coöperate with said auxiliary guides.

35 10. In an automatic train pipe coupling, the combination with a coupler head and guides carried thereon, of auxiliary guides, means normally holding said auxiliary guides in a given relation to the first-mentioned guides, and means permitting movement of said guides to enable either set of guides to coöperate with an opposing coupler.

40 45 11. In an automatic train pipe coupling, the combination with a coupler having a head provided with a central opening communicating with the train pipe and having also auxiliary guides symmetrically disposed on opposite sides of said opening, of pin and funnel guides mounted on said head for the purpose set forth.

50 55 12. In an automatic train pipe coupling, the combination with a base, of a spiral spring seated on the base and extending forwardly therefrom, a head carrying suitable guides supported at the forward end of said spring, and a stem extending rearwardly of said head and carrying auxiliary guides.

60 13. In an automatic train pipe coupling,

the combination with a base, of a spiral spring seated in the base and extending forwardly therefrom, a head carrying suitable guides supported at the forward end of said spring, and a pipe extending through said head and carrying auxiliary guides movable relatively to said suitable guides, for the purpose set forth.

14. In an automatic train pipe coupling, 70 the combination with a coupling head having pin-and-funnel guides and means for flexibly supporting the same, and a coupling head having differently constructed guides and a flexible support therefor, of auxiliary guides on one of said coupler heads adapted to coöperate with the guides of the other head to bring the couplers in the proper register.

15. In an automatic train pipe coupling, 75 the combination with a coupling head carrying diagonally opposite convex surfaces adapted to receive correspondingly shaped guides on an opposing head, of guiding means for said coupling head movable relative to said convex surfaces.

80 16. In an automatic train pipe coupling, 85 the combination with a coupling head carrying diagonally opposite convex surfaces terminating approximately flush with the rear face of said head and having shoulders lying substantially in the horizontal and vertical planes for coöperating with correspondingly shaped guides on an opposing head, of interlocking means for said coupling head adapted to rotate relatively to 90 said convex surfaces in coupling.

17. In an automatic train pipe coupling, 95 means for adapting a coupler of one type to interlock with a coupler of a different type comprising auxiliary guides on the former coupler adapted to interlock with the usual guides upon the latter coupler.

18. In an automatic train pipe coupling, 100 the combination with a coupler having pin-and-funnel guides, of a coupler having wing-guides and auxiliary guides on one of said couplers adapted to coöperate with the guides of the other coupler.

105 19. In an automatic train pipe coupling, 110 the combination with a coupler having pin-and-funnel guides, of auxiliary guides to adapt said coupler to coöperate with a coupler having wing-guides.

In testimony whereof I affix my signature in presence of two witnesses.

JOSEPH V. ROBINSON.
